ELECTRIC SWITCH

Harry B. Speaker, Neptune, N. J., assignor to the
United States of America as represented by the
Secretary of the Army

Application October 12, 1949, Serial No. 121,045

6 Claims. (Cl. 200—52)

(Granted under the act of March 3, 1883, as
amended April 30, 1928; 370 O. G. 757)

1

The invention described herein may be manufactured and used by or for the Government for governmental purposes, without the payment to me of any royalty thereon.

My invention relates to electric switches wherein an electric circuit may be opened or closed by subjecting the switch to acceleration for a period of time. Although said switch is particularly useful in an ordnance projectile, or the like, for the purpose of closing an electric circuit for detonating its war head, its usefulness is not limited thereto.

The present invention is made up of two chambers which intercommunicate through a conduit pierced by a restricted delay channel. Said chambers and channel contain a mobile electrical conductor (such as mercury). Each chamber also contains a gas (such as air) which is more rarified in one chamber ("lower pressure" chamber) than in the other ("higher pressure" chamber). As a result of this pressure differential, when the switch is unoperated (at rest), said mobile conductor is maintained in a condition of balance, at different levels or heights in the two chambers. For convenience I will refer to these levels in the two chambers as "unoperated" levels.

When the device is subjected to acceleration, said mobile conductor flows from the lower pressure chamber to the higher pressure chamber, until a new condition of balance is effected, with said mobile conductor at other levels in the two chambers (which I will refer to as "operated" levels). This flow requires a certain length of time, which is a function of the viscosity of the mobile conductor, the pressure differential, the relative heights of the mobile conductor in the two chambers, the cross-sectional size of the delay channel and the degree of acceleration applied.

One or more electrical terminals are suitably positioned in one or both chambers so as to be in electrical contact with the mobile conductor, either in its unoperated condition (at rest) or in its operated condition (after the application of acceleration for a requisite period of time). If, in the unoperated condition, said mobile conductor is in contact with a terminal, then a circuit incorporating said terminal may be opened upon the application of a predetermined amount of acceleration. If, however, in the unoperated condition, the mobile conductor is not in contact with a terminal, then the closing of a circuit may be accomplished by acceleration.

An object of the present invention is to provide

2

an electrical switch operated by acceleration and, more particularly, to provide such a switch having a time delay.

Another object is to provide such an acceleration actuated switch, wherein a circuit may be either opened or closed.

Still another object is to provide such a switch which returns to its at rest, or unoperated, condition after acceleration has ceased and, particularly, which returns to its said unoperated condition without having effected any circuit change, in the event that an insufficient amount of acceleration has been applied.

Yet another object is to provide such a switch which may be relatively small in size, simple, inexpensive and completely enclosed, and which need have no moving structural parts.

In the drawings, which are drawn to an enlarged scale:

20 Figure 1 is a vertical cross section of one embodiment of the present invention in an at rest or unoperated condition.

Figure 2 shows the embodiment of Figure 1 in its operated condition (after having been subjected to a requisite amount of acceleration),

25 Figure 3 is a vertical cross section of a second embodiment of the present invention in its at rest or unoperated condition; and

Figure 4 similarly shows said second embodiment when sufficient acceleration has been applied to operate it.

Referring now to Figures 1 and 2, the first embodiment of the present invention there illustrated comprises cylindrical lower pressure and higher pressure chambers 11, 13 which intercommunicate by way of a conduit or tube 15 pierced by a relatively restricted delay channel 16. The walls of said chambers 11, 13 and tube 15 may be of any suitable dielectric material (such as glass or plastic) which has sufficient structural strength to take the strains of operation of the device.

The chambers 11, 13 are partially filled with mercury 17, or some other suitable mobile electrical conductor which may flow through the delay channel 16. When in its unoperated condition (i. e. when it is at rest), there is a higher head or level of mercury 17 in the lower pressure chamber 11 than in the higher pressure chamber 13, because a suitable gas 18 (as air) in the space above the mercury in the chamber 11 has been rarified to a greater degree than a gas 20 in the chamber 13.

The lower pressure chamber 11 is provided with 55 two electrical terminals 19 which extend through

the walls of said chamber and are suitably hermetically bonded to said walls. The higher pressure chamber 13 is likewise provided with a pair of electrical terminals 21. It will be noted that the terminals 19 are located below the unoperated level of the mercury 17 in chamber 11 (as shown in Figure 1), but above the operated level of the mercury in said chamber 11 (as shown in Figure 2). Similarly the terminals 21 in the higher pressure chamber 13 are located intermediate the unoperated and operated levels (shown respectively in Figures 1 and 2) of the mercury 17 in said chamber 13.

Referring now to Figures 3 and 4 of the drawing, the second form of my invention there illustrated is made up of a cylinder 23, of glass or other suitable dielectric material, which is subdivided into a lower pressure chamber 25 and a higher pressure chamber 27 by a horizontal wall 29. The two chambers 25, 27 intercommunicate by way of a vertically disposed tubular conduit 31, which extends downwardly from said wall 29 almost to the bottom of said chamber 27, and is pierced by a delay channel 32.

Each of the chambers 25, 27 is partially filled with mercury 33, or some other suitable mobile conductor which may flow through the delay channel 32. The lower end of the tube 31 extends down far enough so that it is always submerged in the mercury 33 at any operating level of the mercury in the higher pressure chamber 27. The gas 35 above the mercury 33 in the lower pressure chamber 25 has a lower pressure than the gas 37 in the higher pressure chamber 27, with the result that, when unoperated, there is a relatively high level of mercury 33 in said chamber 25 and a relatively low level of mercury in said chamber 27.

Extending through the side walls of the lower pressure chamber 25 and hermetically sealed therein are a pair of electrical terminals 39. The higher pressure chamber 27 is similarly provided with a pair of electrical terminals 41. Said terminals 39 are positioned intermediate the unoperated and operated levels (shown respectively in Figures 3 and 4) of mercury 33 in the chamber 25, and, similarly, the terminals 41 are located at a position which is intermediate the unoperated and operated levels of mercury in the chamber 27.

Although not shown in the drawing because not necessarily a part of the present invention, a device embodying the present invention would, in some applications, be mounted in gimbals so as to maintain the device level at all times.

In the operation of the form of my device illustrated in Figures 1 and 2, the elements are as shown in Figure 1 when the device is at rest (unoperated). Due to the differential pressure of the gases 18, 20 in the chambers 11, 13, the mercury 17 achieves a state of balance at the unoperated levels shown in Figure 1. As there shown, the level of the mercury 17 is higher in the lower pressure chamber 11 than in the higher pressure chamber 13. The terminals 19 and/or 21 may be connected into any suitable circuit or circuits (not shown). As, when unoperated, the terminals 19 are submerged in the mercury 17, any circuit connected thereto is closed at said terminals. However, as the terminals 21 are then above the unoperated level of the mercury 17 in the higher pressure chamber 13, any circuit connected through said terminals is open.

During operation, the device is subjected to an acceleration. When this occurs, mercury 17 flows

from the lower pressure chamber 11 to the higher pressure chamber 13. In view of the relatively small size of the delay channel 16 as compared to the viscosity of the mercury 17, this flow will continue for a finite period of time until a new state of balance is reached (Figure 2). It will be seen, that the terminals 19 are now above the operated level of the mercury 17 in the lower pressure chamber 11 so that any circuit in which they are connected will have been opened. Also, the terminals 21 are now submerged in the mercury 17 in the higher pressure chamber 13 so that any circuit in which they are connected will have been closed. As soon as the acceleration ceases, the differential pressure of the gases 18, 20 will cause the mercury 17 to flow back to the unoperated levels (Figure 1).

It will be understood that a certain combination of acceleration and time are necessary before the mercury 17 reaches the operated levels (Figure 2), so as to effect electrical disconnection of the terminals 19 and connection of the terminals 21. Obviously this may be calculated in advance, and the sizes of the chambers 11, 13, the cross sectional area of the delay channel 16, the amount of mercury 17, the relative pressures of the gases 18, 20, the relative positions of the terminals 19, 21 and other factors may be chosen to meet any desired operating characteristics. The basic principle of operation, however, will remain the same.

Although two sets of terminals 19, 21 have been shown, it will be understood that this is merely illustrative and a particular embodiment may have only one of the sets or, if two sets are provided, only one may be used. Also one terminal of each set 19, 21 may be at a lower level so as to be submerged in the mercury 17 during all stages of operation. Again, a plurality of terminals may be used so as to achieve any desired sequential operation. Thus, for instance, several sets of terminals (not shown) may be disposed at different levels so as to open or close circuits at different time intervals.

The operation of the second embodiment (Figures 3 and 4) is similar to the operation already described, the lower pressure and higher pressure chambers 25, 27 being similar to the chambers 11 and 13, respectively, of Figures 1 and 2. This second embodiment may be considered more satisfactory for some installations, because of its compactness and unitary form, and it also has the advantage of having the conduit 31 disposed entirely within the cylindrical structure so as to be less subject to damage.

The present invention may be used irrespective of the direction in which the acceleration is applied. Thus, in a projectile which should reach a certain altitude before its war head is triggered, the acceleration acts in a vertical direction. But in a centrifugal machine, the acceleration may be applied horizontally or, as a matter of fact, in any direction. The heights of the mobile conductor are then effective along the axis of acceleration. Thus, in the present patent application, such terms as "unoperated" level, "operated" level, etc., are to be considered relative to a particular axis of acceleration, which may or may not be vertically oriented.

While there have been described what are at present considered to be preferred embodiments of my invention, it will be obvious to those skilled in the art that changes and modifications may be made therein without departing from the invention and it is aimed in the appended claims to

cover all such changes and modifications as fall within the true spirit and scope of the invention.

What is claimed is:

1. An acceleration operated electric switch comprising, a closed lower pressure chamber, a closed higher pressure chamber, a conduit provided with a delay channel interconnecting said chambers, a mobile electrical conductor within said chambers and channel, gas in each of said chambers, the gas in said lower pressure chamber being more rarified than the gas in said higher pressure chamber, said mobile conductor extending, in one of said chambers, to unoperated and operated levels when said switch is in unoperated and operated conditions respectively, at least one electrical terminal in said last-mentioned chamber at a position intermediate said unoperated and operated levels, so that, when said mobile conductor is at one of said levels, it is in electrical contact with said terminal and, when it is at the other of said levels, it is electrically disconnected from said terminal.

2. A switch as defined in claim 1, wherein said chambers are juxtaposed laterally relative to the axis of acceleration.

3. A switch as defined in claim 1, wherein said chambers are arranged in tandem along the axis of acceleration.

4. An acceleration operated electric switch comprising two closed chambers, a conduit provided with a delay channel interconnecting said chambers, a mobile conductor in said channel and chambers, a gas in each chamber, said gas in one chamber being more rarified than said gas in the other, said conductor extending to unoperated and operated levels in each of said chambers, an electrical terminal in one of said chambers positioned intermediate the unoperated and operated levels in said chamber.

5. An acceleration operated electric switch comprising, a closed lower pressure chamber, a closed higher pressure chamber, a conduit provided with a delay channel interconnecting said chambers, a mobile electrical conductor within said chambers and channel, gas in each of said chambers, the gas in said lower pressure chamber being more

rarified than the gas in said higher pressure chamber, said mobile conductor extending, in said lower pressure chamber, to an unoperated level when said switch is in an unoperated condition and to an operated level, which is lower, when said switch is in an operated condition, at least one electrical terminal in said lower pressure chamber at a position intermediate said unoperated and operated levels, so that, when said mobile conductor is at said unoperated level, it is in electrical contact with said terminal and, when said mobile conductor is at said operated level, it is electrically disconnected from said terminal.

6. An acceleration operated electric switch comprising, a closed lower pressure chamber, a closed higher pressure chamber, a conduit provided with a delay channel interconnecting said chambers, a mobile electrical conductor within said chambers and channel, gas in each of said chambers, the gas in said lower pressure chamber being more rarified than the gas in said higher pressure chamber, said mobile conductor extending, in said higher pressure chamber, to an unoperated level when said switch is in an unoperated condition and to an operated level, which is higher, when said switch is in an operated condition, at least one electrical terminal in said higher pressure chamber at a position intermediate said unoperated and operated levels, so that, when said mobile conductor is at said unoperated level, it is electrically disconnected from said terminal and, when said mobile conductor is at its operated level, it is in electrical contact with said terminal.

HARRY B. SPEAKER.
